CLARINET POSITIONER

Harry A. Schmidt, Tallahassee, Fla., assignor to G. Leblanc Corporation, Kenosha, Wis., a corporation of Wisconsin

Filed June 23, 1964, Ser. No. 377,363
10 Claims. (Cl. 84—327)

This invention relates to a novel clarinet positioner for attachment to a conventional clarinet to position the clarinet in correct playing position with respect to a musician's chest and mouth.

A common difficulty of clarinet instructors is the problem of ensuring that their pupils hold the clarinet in correct playing position. One widely accepted clarinet playing position taught by many clarinet instructors is with the clarinet extending downwardly from the player's mouth at an acute angle to his body toward the floor. To maintain this particular clarinet position, it is necessary to hold the clarinet with the elbows close into the body with the forearms extending outwardly from the body, and the right forearm generally parallel to the floor. Unfortunately, the beginning pupil being unaccustomed to this particular position finds his arms tiring easily, his elbows moving away from his sides, and the clarinet moving progressively upwardly toward a horizontal position with a resultant undesirable change in position of the clarinet mouthpiece between the pupil's lips.

To a lesser extent, the same problem plagues the experienced musician who may be required to hold the clarinet in position for hours on end while playing in the band or orchestra. The problem is accentuated where a conventional lyre or sheet music holder is attached to the clarinet, since the weight of the sheet music acting through the extended lyre tends to pull the clarinet down from the musician's mouth.

As will be appreciated, even minor changes in relative position of the mouthpiece of the clarinet with respect to the musician's lips tend to change the quality and volume of the notes issuing from the clarinet with perceptible and undesirable variations from the rich and expressive tones for which the clarinet is noted.

Thus, a broad object of the invention is to provide means to hold a musical wind instrument in a predetermined position with respect to the musician's body and lips.

A more specific object of the invention is to provide a novel clarinet positioner to support the weight of the clarinet and to aid the player in holding the clarinet in a predetermined position with respect to his body and lips.

Another object is to provide a simple and relatively low cost clarinet positioning device which may be readily secured to a conventional clarinet to position the clarinet with respect to a musician's body so that the mouthpiece may be easily and repeatedly returned to an identical position between the musician's lips.

A further object is to provide means to support a clarinet from a musician's chest and neck in a predetermined position with respect to his body.

Another object is to provide novel clarinet positioning means to assist the musician in holding the clarinet in a predetermined position relieving his arms, fingers and lips from some of the stresses to which they may be exposed with the fingers relatively free to manipulate the keys and the lips relatively more relaxed in an identical desired playing position about the mouthpiece to more readily achieve the rich and expressive tones for which the clarinet is noted.

Another object is to provide means to assist the be-

2

ginning clarinet student in repeatedly achieving and maintaining a substantially identical predetermined clarinet position in which the student is able to devote relatively more attention to the quality of music he is playing rather than to the mechanics of positioning and maintaining the instrument between his lips.

These and other objects of the invention will become apparent from the following description taken in conjunction with the appended claims and drawings illustrating a preferred embodiment of the invention, wherein:

FIG. 1 is a side perspective view of an embodiment of the invention operatively in position on a clarinet;

FIG. 2 is a front perspective view on a larger scale of the embodiment shown in FIG. 1;

FIG. 3 is an enlarged rear elevational sectional view of the device shown in FIG. 2 taken along lines 3—3 of FIG. 2;

FIG. 4 is a sectional view taken along the lines 4—4 of FIG. 3;

FIG. 5 is a sectional view taken along lines 5—5 of FIG. 4.

Detailed description of the invention

Referring to the drawings, there is shown in FIG. 1 an embodiment of the invention operatively in position about a B-flat clarinet with means shown to support a portion of the weight of the clarinet from the neck and chest of a musician holding the clarinet in playing position.

The B-flat clarinet shown includes a mouthpiece 10, a barrel or upper portion 12, a body upper joint or upper central portion 14, a body lower joint or lower central portion 16 and a lower end or bell 18. The lower joint 16 has an outer metallic reinforcing band 24 at its upper end 22 similar to upper and lower reinforcing bands 23, 25 and is adapted to receive a lower end 20 of the body upper joint slidably therein.

The clarinet positioner of the present invention, FIG. 2, comprises a ring assembly 26 including a generally cylindrical positioning band or ring 28 having a lower notch or cutout portion 30, a forward stud receiving protuberance 32 and a rear shaft receiving protuberance or nut 34, positioned generally diametrically opposite the stud receiving portion 32 on the ring. The ring 28 has a predetermined width generally about the same as that of the reinforcing ring 24, FIG. 5, and has an inner surface 36 generally complementary to and adapted to fit about the outer surface 40 of the reinforcing ring. Ring 28 is adapted to be fitted snugly about the reinforcing ring prior to assembly of the upper and lower joints 14 and 16.

Band 28, FIG. 5, has a perforation 41 centrally positioned with respect to its width and extending from its outer surface 42 to its inner surface 36, the perforation 41 being internally threaded and being in alignment with a complementary internally threaded passageway 43 in stud receiving protuberance 32.

The stud receiving portion 32 is secured to the positioning ring 28 advantageously by brazing or by welding, and is positioned extending generally outwardly from the ring 28 being adapted to receive a threaded stud 45, FIG. 5, of a knurled lyre holder 44, the stud being adapted to be threadedly received into the threaded passageway in the stud receiving protuberance 32 and in the threaded ring perforation 41. Stud 45 has a generally flat end 46, FIG. 5, adapted to be screwed tightly against the clarinet reinforcing ring.

Lyre holder 44 has a threaded opening 47 at its other end, opening 47 being internally threaded to receive a threaded lyre rod 49 to support sheet music from the clarinet in a position where the musician can readily read the music.

The notch 30 provided in the generally cylindrical ring 28, FIG. 4, is adapted to clear a third ring key 48, on the clarinet, sufficient clearance being provided so as not to interfere with movement of the key.

Shaft receiving nut 34, FIGS. 3-4, is attached to ring 26 by means of a generally upwardly extending mounting plate or bar 50 which stabilizes the clarinet with respect to the ring 26. Bar 50 and nut 34 are conventionally welded or brazed together, bar 50 then being secured to the ring by conventional means such as brazing or welding.

Bar 50, FIGS. 2, 4, is generally rectangular in shape and has an inner surface 52 complementary to the outer surface 54 of the clarinet, the bar being secured to ring 28 in a position extending upwardly and generally perpendicular to the circumference of the ring 28, that is, extending upwardly in the same general direction as the clarinet. Bar 50 is provided advantageously, but not necessarily, with upper and lower internally threaded screw openings 56 and 58, respectively. The openings are adapted to receive screws, not shown, to bear against the outer clarinet surface 54 or to be screwed into the clarinet to hold the plate into position and to stabilize positioning band 28 with respect to the clarinet.

Shaft receiving nut 34 has an inner end 60 and an outer portion 62, the outer portion having an internally threaded opening 64 adapted to receive a threaded end 66 of a bracing plate shaft 68. The threaded end 66 is of a relatively smaller diameter than the balance of the shaft 68 and is threadedly inserted into the nut in a position at a right angle to the clarinet to properly position the shaft 68 to support the clarinet.

Shaft 68 has a rear end 70 which is pivotally secured, as by riveting, to a generally circular chest plate or disc 72, FIG. 2, with the shaft perpendicular to and extending outwardly and forwardly with respect to the plate. The plate 72 has an upper segment 74 which is bent or turned forward toward the forward threaded end 66 of the segment having a central generally circular perforation 76 adapted to receive a hook or snap connector 78 secured to a lower end of a leather strap 80 adapted to fit around a player's neck, the strap 80 being shown with a buckle 82 and a neck band 84, the buckle being provided for vertical adjustment of the snap connector and the chest plate 72, the neck band providing a broader cushioned area about the musician's neck from which to support the snap connector and chest plate.

Operation of the invention

From the above description of an embodiment of the invention, its operation should be clear; however, for purposes of an easier understanding of the invention, a functional description of the invention is now provided.

A positioner for a musical wind instrument has been provided including a generally cylindrical ring assembly 26, FIG. 2, adapted to fit around a conventional clarinet reinforcing ring. The ring assembly is positioned about the reinforcing ring of the clarinet, a knurled thumb screw or lyre holder 44 is tightened threadedly into a stud receiving protuberance 32 to bear against the clarinet reinforcing ring 24 locking the ring clampingly in position against the clarinet reinforcing ring. The ring assembly is fixedly secured to one end of a shaft secured at its other end to a chest piece adapted to fit against the chest of a musician. A generally upright plate 50 is secured to the ring in position to fit against the clarinet to stabilize the ring with respect to the clarinet and to prevent movement of the ring assembly on the clarinet. The chest piece shaft is advantageously angled at about a right angle to the chest piece and the clarinet so as to correctly position the musical instrument with respect to the musician's chest and lips.

The chest disc is connected to a strap encircling the musician's neck, the weight of the clarinet being supported from the neck and chest of the musician to permit a re-

positioning of the clarinet in substantially the same position desired each time it is played with respect to the musician's body and lips. Thus, the clarinet positioner assembly relieves the arms and hands of the weight of the clarinet leaving them free to manipulate the keys of the instrument.

Since many modifications of the invention described above and illustrated in the various figures may be made, the invention should not be limited thereto; and it is contemplated by the appended claims to cover any modifications as fall within the true spirit and scope of the invention.

The invention is hereby claimed as follows:

1. A positioner for a musical wind instrument, said positioner comprising: a positioning band adapted to fit around said instrument; means to secure said band to said musical instrument; a shaft secured to said positioning band in a position extending radially outwardly from the band, said shaft having a rear end spaced apart from the end secured to the positioning band; a chest disc adapted to fit against the chest of a musician holding the musical instrument, said disc being secured to the far end of said shaft in a position with the shaft extending radially outwardly from the plate and from the musician's chest; and means connected to the disc to support the disc from about the musician's neck.
2. The positioner of claim 1 including stabilizing means secured to said band to stabilize the band and to prevent movement of the band with respect to the instrument.
3. The positioner of claim 1 wherein said clamping means comprises a lyre holder threadedly inserted into a threaded opening provided in said positioning band, said lyre holder being adapted to be screwed tightly into said positioning band to bear against said reinforcing ring in a position diametrically opposite to the position of said shaft on said band.
4. A positioner for a musical wind instrument comprising a clarinet, said clarinet having an upper central portion and a lower central portion, said upper central portion being adapted to be connected to said lower central portion, said clarinet also having a centrally located outer reinforcing ring positioned on the upper end of said lower central portion; said positioner comprising: a generally cylindrically shaped positioning band having an inner surface generally complementary to and adapted to fit over said central reinforcing ring; a chest plate adapted to be suspended from about a musician's neck, said chest plate being connected to one end of a shaft connected at its other end to said positioning band; and means connected to said chest plate to move said chest plate upwardly or downwardly with respect to a musician's lips and chest.
5. A positioner for a musical wind instrument having a centrally located outer reinforcing ring and having a third ring key pivotally secured to said instrument in a position below and adjacent to said reinforcing ring, said positioner comprising: a positioning band adapted to fit snugly over said reinforcing ring, said ring having a lower notch adapted to fit about said third ring key with a predetermined clearance above an upper end of said key to permit the key to be operated freely; clamping means secured to said band adapted to hold said band securely to said reinforcing ring, said clamping means including a lyre holder positioned on said clarinet in outwardly extending position with respect to a musician holding said instrument in playing position; a shaft having a far end and a band end, said band end being fixedly secured to said band and extending radially outwardly from said band in a position diametrically opposed to the position of said lyre holder; a chest plate adapted to fit against the chest of a musician, said chest plate having an outer surface attached to the far end of said shaft; and means connected to said chest plate to suspend said plate from about a musician's neck and to move said chest plate upwardly or downwardly with respect to said musician's

neck so as to position said instrument with respect to said musician's chest and lips.

6. The positioner of claim 5 wherein said shaft is secured to said ring in a position generally perpendicular to said instrument and including stabilizing means secured between said band and said band end of said shaft to stabilize said band with respect to said clarinet, said stabilizing means having an inner surface adapted to fit snugly against said clarinet surface.

7. A positioner for a clarinet, said clarinet including a mouth piece, an upper portion, an upper central portion, a lower central portion, and a lower end having a bell-shaped opening therein, said lower central portion having an upper end adapted to receive a complementary portion on the lower end of said upper central portion, said upper end of said lower central portion having a centrally located outer reinforcing ring, said positioner comprising: a positioning band adapted to fit slidily over said central reinforcing ring when said lower central portion is disassembled from said upper central portion, said band being adapted to fit snugly about said reinforcing ring, said band having a generally circular circumferential perforation; clamping means secured to said band in the area around said perforation, said clamping means being adapted to be inserted into said perforation to clampingly secure said band to said clarinet, said clamping means including a protuberance secured to said band in an outwardly extending position, said protuberance being internally threaded to receive a threaded stud; a lyre holder forming part of said clamping means, said lyre holder including a threaded stud, said threaded stud being generally complementary to and adapted to fit threadedily into said internally threaded protuberance and to bear clampingly against said reinforcing ring to secure said band to said reinforcing ring and said clarinet; a shaft of a predetermined length and having a forward end and a rear end, said forward end being secured to said band in a position diametrically opposed to said band perforation, said rear end of said shaft being secured to a chest plate; a chest plate having an inner surface adapted to fit against the chest of a musician and having an outer surface secured to the rear end of said shaft, said chest plate comprising a generally flat disc, said disc having an upper portion extending outwardly with respect to a musician's chest, said upper portion being centrally perforated, said central perforation being adapted to receive a connector secured to a neck band hung about the neck of said musician, said neck band and said connector having adjustment means to adjust the position of said chest plate upwardly or downwardly with respect to said musician's neck and lips, whereby said clarinet may be correctly positioned with respect to said musician's lips and body in a predetermined playing position.

8. The positioner of claim 7 wherein said positioning band has a lower notch adapted to fit over a centrally located clarinet third ring key pivotally secured to the lower central portion of said clarinet, said band having an upper end in close proximity to said reinforcing ring, said notch being adapted to clear said third ring key so as to permit free operation of said third ring key.

9. A positioner for a clarinet, said clarinet including a mouth piece, said clarinet having a centrally located outer reinforcing ring and a third ring key pivotally secured to a lower central portion of said clarinet, said third ring key having an upper end in close proximity to said reinforcing ring; said positioner comprising: a generally cylindrically shaped positioning ring having an inner surface generally complementary to said reinforcing ring, said positioning ring being adapted to fit over said central reinforcing ring and having a lower notch adapted to fit with a predetermined clearance above the upper end of said third ring key, said positioning ring having a generally circular perforation extending through said positioning ring from said outer circumference to the inner circumference; a stud-receiving protuberance extending out-

wardly from said cylindrical ring and having an inner passageway adapted internally to threadedly receive threaded stud means to bear against said clarinet reinforcing ring to hold said clarinet positioning ring clampingly about said reinforcing ring and said clarinet; a lyre holder having an externally threaded stud, said lyre having a body portion having a threaded opening therein adapted to receive a threaded end of a lyre, said stud being operatively threadedly positioned in said positioning ring perforation to bear against said clarinet; a shaft receiving protuberance secured to the outer surface of said positioning ring in a position generally diametrically opposed to the position of said perforation and said lyre holder, said protuberance having an internally threaded bore therein adapted to receive a threaded shaft; a shaft of a predetermined length and having an externally threaded forward end threadedly inserted into said threaded bore, said shaft also having a rear end; a chest plate fixedly secured to the rear end of said shaft and having a rear surface adapted to rest against the chest of a musician holding said clarinet; and means connected to said plate to suspend said plate from about the neck of said musician, whereby said shaft and said positioning band correctly positions said clarinet with respect to said musician's body and lips when said mouth piece is inserted between said musician's lips.

10. A positioner for a musical wind instrument, said instrument including a mouthpiece, an upper central portion and a lower central portion, said upper end of said lower central portion having an outer reinforcing ring and having a key pivotally secured to said lower central portion, said key having an upper end in close proximity to said reinforcing ring; said positioner comprising a generally cylindrically shaped positioning band having an inner surface generally complementary to said reinforcing ring and adapted to fit over said ring when said lower central portion of said instrument is disassembled from said upper central portion, said band being so shaped as to fit slidily over said ring, said band having a lower notch adapted to fit with a predetermined clearance above said upper end of said key, said band having a generally circular perforation extending through said ring from said outer circumference to the inner circumference of said ring; a stud-receiving protuberance extending outwardly from said ring and being secured to said ring in the area around said ring perforation, said protuberance being internally threaded to threadedly receive instrument clamping means; means secured to said ring at a position diametrically opposed to said stud-receiving protuberance to stabilize said ring on said instrument, said means comprising an upwardly extending plate having an inner surface adapted to fit snugly against the outer surface of said instrument, said plate being positioned on said cylindrical ring in a position generally perpendicular to the circumference of said ring, said plate being generally rectangular in shape and having an upper end and a lower end, said ends each having threaded openings therein adapted to receive a screw to fixedly secure said plate to said instrument, a protuberance mounted on said plate, said protuberance comprising a shaft-receiving portion secured by said plate to the outer surface of said ring in a position generally diametrically opposed to the position of said stud-receiving portion, said protuberance having an internally threaded passageway adapted to receive a threaded shaft; a shaft of a predetermined length and having a forward end and a rear end, said forward end being externally threaded and being threadedly inserted into said shaft receiving portion on said ring; a chest plate fixedly secured to the rear end of said shaft and having a rear surface adapted to rest against the chest of a musician holding said instrument, said plate being generally circular in shape and being positioned on said shaft with said shaft extending axially outwardly from said plate, said plate having an upper segment thereof extending

generally forwardly toward the forward end of said shaft, said forwardly extending segment having a perforation therein adapted to receive a connector from a neck band of said musician; clamping means to hold said band fixedly in position on said instrument, said means comprising a thumb screw having a threaded stud at one end and having a threaded passageway at its other end, said threaded stud being adapted to fit threadedly into said stud-receiving portion and said perforation of said ring, the forward end of said stud being generally flat and being

adapted to fit clampingly against said reinforcing band when said thumb screw is threaded into position in said stud-receiving portion, the internally threaded other end of said thumb screw being adapted to receive a threaded lyre to hold sheet music in position to be read by said musician holding said instrument.
